UNITED STATES PATENT OFFICE.

JOSEPH C. DOBY, OF GRAND VALLEY, COLORADO.

GAMBREL.

1,206,820.

Specification of Letters Patent.

Patented Dec. 5, 1916.

Application filed May 6, 1916. Serial No. 95,857.

To all whom it may concern:

Be it known that I, JOSEPH C. DOBY, a citizen of the United States, residing at Grand Valley, in the county of Garfield and State of Colorado, have invented certain new and useful Improvements in Gambrels, of which the following is a specification, reference being had to the accompanying drawings.

This invention relates to certain improvements in gambrels and it is an object of the invention to provide a device of this general character having novel and improved means whereby the carcass to be suspended may be elevated with a minimum of effort.

Furthermore it is an object of the invention to provide a novel and improved device of this general character wherein a flexible hoisting member is employed and wherein automatic means coact with said flexible hoisting member for maintaining the carcass in elevation.

The invention consists in the details of construction and in the combination and arrangement of the several parts of my improved gambrel whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein—

Figure 1 is a view partly in elevation and partly in section illustrating a gambrel constructed in accordance with an embodiment of my invention; Fig. 2 is a diagrammatic view illustrating the arrangement of the flexible member M as herein embodied; Fig. 3 is a longitudinal sectional view taken through the device as herein disclosed with certain of the parts omitted and other parts shown in elevation; Fig. 4 is a fragmentary longitudinal sectional view taken at right angles to the section in Fig. 3; Fig. 5 is an elevational view of the outer end of one of the blocks as herein included with certain of the parts omitted for clarity in disclosure; Fig. 6 is a sectional view taken through the holding member herein employed; and Fig. 7 is a sectional view taken substantially on the line 7—7 of Fig. 6.

As disclosed in the accompanying drawings, 1 denotes a block of predetermined dimensions preferably substantially rectangular in form and provided at one end with an opening 2 to afford means whereby said block 1 may be supported in a desired position and further provided with a series of longitudinally alined openings 3 in each of which is mounted a pulley 4.

The lower end of the block 1 is provided with the longitudinally disposed opening 5 in communication with the adjacent opening 3 for a purpose which will hereinafter be explained.

6 denotes a second elongated block having its upper portion provided with a longitudinal bore 7 below which is arranged a series of longitudinally alined openings 8 preferably two in number and in each of which is mounted a pulley 9. The longitudinal or side faces of the block 6 are provided intermediate their lengths with the slots 10 in communication with the bore 7 and extending a predetermined distance inwardly of the lower end of said bore. The upper end of the block 6 is bifurcated and rotatably mounted within the kerf 11 are the pulleys 12 disposed at opposite sides of the bore 7 for a purpose which will herein-after be self-evident.

The side faces of the block 6 in close proximity to the inner or lower end of the bore 7 are provided with the outwardly and oppositely directed pairs of ears 14 between each pair of which is rotatably mounted the pulley 15.

The lower portion of the block 6 is preferably enlarged transversely and has the outer or lower portions thereof at opposite sides of its transverse center reduced in thickness, as indicated at 16, to afford webs 16 adapted to extend within the kerfs 17 of the bifurcated inner extremities of the spreading arms 18, said spreading arms 18 being pivotally engaged, as at 19, with said webs. The outer or free ends of the spreading arms 18 have pivotally engaged therewith the hooks 20 adapted to be engaged in a conventional manner with the carcass to be suspended.

One of the spreading arms 18 has secured to its inner face and adjacent its free end the bracket 21 with which is pivotally engaged the arm 22 extending through an opening 23 produced in the second spreading arm 18, and the lower face of said arm 22 is pro-

vided with the teeth 24 adapted to engage by gravity the catch pin 25 intersecting the opening 23 whereby it will be perceived that as the spreading arms 18 are separated, 5 the arm 22 serves to prevent inward or retrograde movement of said spreading arms.

Secured to the outer face of each of the spreading arms 18 adjacent the lower ends thereof is an extremity of a flexible member 10 26 which extends within the bore 7 through the lower portion of the slots 10 and beneath the pulleys 15, whereby it will be perceived that upon upward movement of the flexible members 26 within the bore 7, the spreading 15 arms 18 will be caused to separate. The upper or connected extremities of the flexible members 26 are suitably secured to the portion 27 of the flexible member M, said portion 27 being disposed through the bore 20 7 of the block 6 and upwardly through the opening 5 of the block 1 and over the pulley 4 in the opening 3 immediately adjacent the lower end of the block 1. The member M is then extended downwardly, as indicated at 25 28, and passes under the upper pulley 9. The flexible member M is then extended upwardly, as indicated at 29, and is extended over the second pulley 4 above the lower end of the block 1 and continues downwardly, as indicated at 30, and passes beneath the lower pulley 9, as at 31. The flexible member M is then continued upwardly, as indicated at 32, and passes over the uppermost pulley 4 and is then extended, 35 as at 33, to a locality whereby the requisite pull may be imposed upon the member M for elevating or raising the block 6 and the carcass with which the spreading arms 18 may be engaged.

40 34 denotes a block adapted to be suitably anchored and having one end portion provided with a bore 35 in communication with a recess 36 in a side of said block 34 and in which recess 36 is rotatably mounted the pulley 37. The portion 33 is directed through the bore 35 and out through the recess 36 beneath the pulley 37. At a point above the recess 36 the opposite sides of the block 34 are provided with the openings 38 45 also in communication with the bore 35 whereby means is afforded to permit the jaws 39 to engage the part 33 of the flexible member M in order to prevent return movement of said portion 33 of the flexible member M which would otherwise result in the lowering or downward movement of the block 6 and the carcass supported thereby. The jaws 39 are normally forced inwardly to operatively engage the flexible member 50 55 M through the medium of the expandible members 40 herein disclosed as conventional coil springs interposed between the side faces of the block 34 and the upwardly extending tails 41 of the jaws 39.

60 65 It is to be noted that the returned portions

29, 30, 31 and 32 overlie opposite faces of the blocks 1 and 6 and in order to prevent entanglement of these returned portions, I find it of particular advantage to provide the opposite faces of said blocks 1 and 6 at 70 their opposed ends with the transversely directed plates 42 provided in their under faces with the channels 43 disposed longitudinally of the blocks 1 and 6 and through which the returned portions 29, 30, 31 and 75 32 of the flexible member M are disposed.

In the operation of the device, the hooks 20 are properly engaged with a carcass whereupon the requisite pull is imparted upon the flexible member M which results 80 in the elevation of the block 6. When the block 6 comes into contact with the block 1, the continued pull upon the flexible member M will result in an upward or separating movement of the arms 18 so that it will be 85 perceived that the carcass may be readily and effectively suspended in a desired manner.

From the foregoing description, it is 90 thought to be obvious that a gambrel constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice. 95

I claim:

1. A device of the character described including a block having an end portion thereof provided with a bore and with openings in its sides in communication with the bore, spreading arms pivotally engaged with the opposite end portion of the block, flexible members secured to the outer end portions of the spreading arms and extending within the bore of the block through the openings in the side thereof, a lifting means for the block including a flexible member extending within the bore of the block and secured to the first named flexible member, and a member engageable with the block when elevated a predetermined distance whereby a continued operation of the lifting means causes an upward movement of the spreading arms through the medium of the first mentioned flexible members and the second named flexible member. 110

2. A device of the character described including a block having an end portion thereof provided with a bore and with openings in its sides in communication with the bore, spreading arms pivotally engaged with the opposite end portion of the block, flexible 115

120 125 130

members secured to the outer end portions of the spreading arms and extending within the bore of the block through the openings in the side thereof, a lifting means for the block including a flexible member extending within the bore of the block and secured to the first named flexible member, a member engageable with the block when elevated a predetermined distance whereby a continued 10 operation of the lifting means causes an upward movement of the spreading arms through the medium of the first mentioned flexible members and the second named flexible member, and guide pulleys positioned above the inner end of the bore of the block above the openings therein and beneath which the first named flexible members are directed.

3. A device of the character described including a block having an end portion thereof provided with a bore and with openings in its sides in communication with the bore, spreading arms pivotally engaged with the opposite end portion of the block, 20 flexible members secured to the outer end portions of the spreading arms and extending within the bore of the block through the openings in the side thereof, a lifting means for the block including a flexible member extending within the bore of the block and secured to the first named flexible member, a member engageable with the block when

elevated a predetermined distance whereby a continued operation of the lifting means causes an upward movement of the spreading arms through the medium of the first mentioned flexible members and the second named flexible member, and pulleys rotatably supported by the block at opposite sides of the bore and adjacent the outer end 35 of the bore.

4. A device of the class described comprising a block provided with securing means, a second block, spreading arms pivotally supported by the second block, 40 flexible members secured to the outer portions of the spreading arms, guiding members carried by the second block and beneath which the flexible members are disposed, a second flexible member operatively 45 engaged with the first named flexible member and comprising returned portions operatively engaged with both of the blocks whereby pull upon said flexible member elevates the second named block relative to 50 the first named block and elevates the spreading arms upon contact of the second named block with the first named block.

In testimony whereof I hereunto affix my signature in the presence of two witnesses. 55

JOSEPH C. DOBY.
